UNITED STATES PATENT OFFICE

JOHN D. PUGL, OF BALTIMORE, MARYLAND

CAR DUMPING APPARATUS

Application filed September 22, 1928. Serial No. 307,560.

The present invention relates to car dumping apparatus and particularly to apparatus of this character intended for use at or near coal mines for dumping loaded mine cars.

5 Coal is usually handled at the larger coal mines by means of trains of cars which are drawn by locomotives from the mine to a receiving point where the cars are discharged of their contents and the empty cars returned 55 to the mine for reloading. The object of the present invention in general is to provide an apparatus which will dump the cars of such a train as they are successively passed therethrough while still coupled together and 60

15 which will operate on the cars smoothly and with a minimum expenditure of power.

For the attainment of the above stated general object, the invention provides a coal dumping apparatus comprising, broadly, a 65 helical guide through which the cars are propelled by power means or by gravity and coacting elements on the car which not only constrain the car to rotate about the axis of the helix as it progresses therethrough but 70 support the car in all positions thereof. The parts are so constructed and arranged that the axis of the helical guide passes through the car couplings and also passes through or adjacent to the center of gravity of the car, 75 the result being that the car couplings do not interfere with the relative rotation of the cars and substantially all the power required to propel the cars through the apparatus is expended in overcoming friction.

80 A car dumping apparatus of the above indicated construction is shown in my copending application, Serial No. 184,155, of which the present application is a continuation in part. The construction shown in this copending application comprises a helical guide which acts as the sole support for the cars as they pass therethrough. When a car is rotated by coaction with a helical guide, say in a right hand direction, the center of support 85 of the car shifts to the left of the center of gravity of the car, which produces a moment tending to twist the car in a right hand direction. These twisting moments cause pressure on the helical guide in excess of that 90 due to the direct weight of the car, and neces-

sitate a very strong and rigid construction besides causing excessive friction between the sliding surfaces. The present invention provides means for relieving the guides of these excess pressures, the said means comprising helical bearing surfaces for the cars which are auxiliary to the helical guide, said bearing surfaces being arranged to counteract the twisting moments referred to above.

55 Other improvements effected by the invention will be pointed out hereinafter.

Referring now to the accompanying drawings for a particular description of apparatus embodying the invention:

60 Figures 1 and 1^a constitute a side elevation of a preferred form of the invention, Fig. 1 showing the front half of the apparatus and Fig. 1^a the rear half;

65 Figures 2 and 2^a show a plan of the apparatus with the supporting structure omitted;

70 Figure 3 is a right hand end elevation;

Figure 4 is a sectional view taken on line 4-4 of Fig. 1;

75 Figure 5 is a sectional elevation showing the general layout, with a train of cars passing through the dumping apparatus;

80 Figure 6 is a detail showing a portion of a car and a guide block carried thereby together with a section through a stationary helical guide adapted to coact with said block;

85 Figure 7 shows a car carried guide block in side elevation and plan;

Figure 7^a is a sectional detail, showing a modified form of guide and guide block;

90 Figures 8 and 8^a are sectional views on lines 8-8 and 8^a-8^a, respectively of Fig. 2^a;

95 Figure 9 is a partial plan view of a modified form of apparatus;

Figure 10 is a section on line 10-10 of Fig. 9, showing a car in elevation;

100 Figures 11 and 12 are detail views indicating further modifications;

Figures 13 and 14 are partial plan and side views, respectively, of still another modification; and

Figures 15 and 16 are sectional details of this modification.

Figs. 1 to 7 show the invention in what is at present considered to be its most practical form. However, as will become apparent

hereinafter, many variations and modifications of this particular form are possible in a practical sense. As represented, the dumping apparatus, hereinafter called the dump, comprises a member 20 which has a trough-like formation in cross section. The end portions of this trough-like member, hereinafter termed trough, are straight while its intermediate portion is formed into a continuous helix having one complete turn. The sides of trough 20 are concave, being curved on an axis substantially coincident with the axis A of the helix. The bottom of the trough is flat, as indicated in Fig. 3. Fig. 4 shows the bottom curved, but where this section is taken the trough has a helical form. A section at this point taken on a diagonal line would show the bottom flat.

Trough 20 is supported on double truss frames 21 of rectangular form, these frames being rigidly secured together by longitudinal members 22 and diagonal braces 23. The straight entrance and exit portions of the trough are supported respectively on cross bars 24 of the two end frames 21, while at intermediate points the trough is supported on the frames by pads 25 secured to inclined members 26 (see Fig. 4). To obviate the manufacturing difficulties involved in twisting 30 and bending a rolled plate into the correct helical form, the trough may be cast in several sections. As shown, it is formed in three sections, the abutting ends of which are flanged and bolted together, as at 27 in Figs. 35 2 and 2^a. As indicated in Fig. 5, the framework is supported by a suitable masonry or concrete foundation.

Fixed in trough 20 is a helical guide composed of two guide rails X and Y. These 40 guide rails are generated on axis A, have the same pitch, and are supported parallel to each other, being fixed to opposite sides of a helical rib 28, which may be integral with trough 20. Each rail, as illustrated, consists of a 45 T bar, it being observed, however, that the flanged portions of these bars do not extend at right angles to the webs but are inclined away from each other, the object of this being to reduce the head room that these guide rails 50 occupy under the car and axle and also to permit increased clearance between the coacting slide blocks on the car, hereinafter described, and track rails which these blocks must pass over at switches, crossings and the 55 like.

The cars are of the usual construction, having four wheels, a flat bottom and flaring sides. They are provided with couplings swivelled or otherwise constructed to permit 60 relative rotation of the coupled cars about a common axis. Each car is equipped with two slide blocks 28^x and 28^y which are fixed beneath the car respectively at diagonal front and rear corners thereof, the front block 28^x 65 being adapted to engage guide rail X and the

rear block 28^y being adapted to engage guide rail Y. As shown more clearly in Figs. 6, 7 and 8, each block consists of a base 29 which is flanged and bolted to the car, and a depending portion 30 in which is formed a helical T slot 31 having a pitch equal to that of 70 guide rails X and Y and formed to have an easy sliding fit with the rail. As the two blocks on a car respectively engage the helical guide at longitudinally spaced points thereof, it is obvious that the helical slots in the blocks, while having the same form and pitch, will extend differently with respect to each other so as to conform to the helical guide. Obviously the forms of the guide rail and slide block can be reversed. Fig. 7^a indicates such a modification, showing a guide rail X' 75 formed with a helical T-shaped slot adapted to engage a T-shaped slide block 28^x.

To reduce friction between the guide and blocks, a suitable means for lubricating the guide rails or the blocks should be provided. A particular lubricating means for the rails is illustrated in Fig. 6, comprising a pipe p 80 extending along the web of the rail and having openings communicating with ducts in said web at suitably spaced points, each duct having a number of branches which open at points in the flanges of the rail. Lubricant is forced through pipe p by a pump or by gravity.

The apparatus thus far described is sufficient in itself to rotate the cars of a train successively through a complete revolution as the cars are propelled therethrough, it being noted that the helical guide rails and interfitting car carried blocks are effective not only to constrain the cars in a helical path but to support the cars in all positions thereof. However, to minimize as far as possible the pressures on the guides and blocks generated in the twisting movements of the cars, the present invention provides auxiliary supporting means for the cars. In the form of the invention illustrated, this auxiliary means consists of helical bearing surfaces for the four wheels of the car.

Obviously during the screw movement of a car through the dump the tangent points of the four wheels will describe four separate helices having a common axis which is coincident with the axis of guide rails X and Y, and it is therefore impossible to have the two wheels at one side of the car bear on a single rail or helical surface and of course it is also impossible to have the two wheels at the other side of the car follow a single helical rail. Therefore, helical bearing surfaces for the two right hand wheels of the car are provided by ribs 35 and 36 formed in trough 20 in the front half thereof and helical bearing surfaces for the two left hand wheels are provided by ribs 35' and 36' formed in the rear half of the trough. These ribs provide ledges on which the wheel treads travel. In

125

130

addition to these helical ribs there are provided straight horizontal ribs 33, 33^a and 34 in the entrance end of the trough and corresponding ribs 33', 33'^a and 34' in the exit end 5 of the trough, the ledges of these ribs being aligned with the outside rails 37 which are secured to the ends of trough 20 at 38. As a car enters the dump from tracks 37, the four wheels of the car pass on to the straight 10 ledges of ribs 33, 33^a and 34, until the car reaches the position shown in Fig. 1. In this position the guide rail Y has just entered the guide block 28^y and the guide rail X has just entered the block 28^x, the ends of said 15 guides being separated a distance equal to the distance between the blocks so that the latter will be simultaneously engaged. The ends of the guides are tapered, as indicated in Figs. 1 and 2, to facilitate their entry into 20 the blocks. Upon further movement of the car, the helical guides coacting with the car carried guide blocks will cause the car to turn in a right hand direction, or clockwise, about the axis A, the rear right hand wheel of the 25 car descending and bearing on the rib 36, which is a continuation of rib 33, while the forward right hand wheel follows the descending rib 35, which is a continuation of straight rib 33^a.

30 When the car is twisted to the right from its normal position about the axis of the helical guide, the mean center of support, which is located midway between the guide blocks at the point S (Fig. 3) shifts to the left of 35 the center of gravity of the car. To take care of the excess pressure on the guides which would otherwise be produced by this shifting of the center of support with reference to the center of gravity, it is only 40 necessary to provide bearing surfaces for the right hand wheels during the first 180° rotation of the car, since the moment of force thereby produced tends to rotate the car in a right hand direction. During the last 180° 45 rotation the conditions are reversed, the center of support shifting to the right of the center of gravity, and it therefore becomes necessary to support the left hand wheels in order to relieve the guides. Accordingly 50 Figs 1 and 2 show only ribs 35 and 36 for the right hand wheels, corresponding ribs for the other pair being omitted as superfluous, and rib 34 terminating at the point where the forward left hand wheel leaves it in the initial part of the helical movement. Ribs 35 and 36 terminate near the right hand end of Figs. 1 and 2, or adjacent the transverse center line of the dump, and adjacent this point the ribs 35' and 36' begin and extend 55 to near the exit end of the dump, being continued respectively by the straight ribs 33^a, 33' and 34'. It will be observed that the arrangement of guides and ribs at the exit end of the dump is exactly reversed with respect 60 to that at the entrance end. Obviously,

therefore, cars can be entered at either end.

It will be noted that during the passage of a car into the left hand end of the dump the forward right hand wheel will pass over a gap between the end of rib 33^a and rib 33, 70 this gap being rendered necessary in order to permit the rear wheel to follow the descending rib 36. It will be seen in Fig. 3 that the outer edges of the wheel rims are substantially tangent to the concave faces of trough 20. Therefore, the forward wheel will be guided smoothly over this gap by the engagement of its outer edge with the concave side of the trough. In Fig. 2 it will 75 also be noted that the gauge between the ribs 33 and 34 is larger than that between the outside rails 37. This is for the purpose of providing sufficient clearance between the ribs and the wheel flanges to permit the forward right hand wheel to pass straight over the gap between ribs 33 and 33^a and to permit the left hand wheels to leave rib 34 in the initial helical movement of the car; also to provide clearance between the ribs and the wheel rims (as, for instance, 80 corner of rib 35 and edge of rear right wheel rim when car has fully entered helix, like in Fig. 4).

A suitable receiver or chute 40 is supported on the framework of the dump in a position 95 to catch the coal falling from the car in the overturning movement thereof. The coal is adapted to be deposited from this chute onto a railway car or other receiver. The chute may be of any suitable construction. As illustrated, it has a downwardly tapering form and is eccentrically disposed with respect to the dump, it being located nearer to the forward than the rear end of the dump so as to insure catching of any coal that may be discharged from a car in the initial turning movement thereof. The forward top edge of the chute is secured at 41 to the underside 100 of trough 20, while its rear top edge extends only to the third frame 21 from the right. The rear wall of the chute is cut away, as 105 indicated by the dotted lines 42, Fig. 2^a, to provide clearance for the car body. The sides of the chute are supported from the frames as indicated in Figs. 3 and 4.

Fig. 5 shows the general layout of the dump and adjacent territory. A train of cars is represented as being fed through the dump by a trip feeder F, which comprises a power driven endless chain provided with 110 longitudinally spaced dogs adapted to engage lugs on the cars. The train of cars is drawn up to and beyond the feeder by a locomotive which is then uncoupled and switched onto another track. The feeder will then 115 function to move the train down a slight incline into the dump and the latter will successively overturn and then right the cars, the coal falling into chute 40. The empty cars passing out of the dump are pro- 120

125

130

elled by an empty haul H , which will clear the train through the dump and deliver same to a point ready to be taken by the locomotive back to the mine.

5 As heretofore pointed out, in the present apparatus the center of gravity of the car is designed to be located on or adjacent to the axis of the helix, or axis of rotation of the car, so that substantially all the force necessary to propel the car through the helix is expended in overcoming friction. It is to be observed, however, that the center of gravity of the loaded car may be raised substantially above the axis of rotation to thereby 15 cause the weight of the car to assist its dumping. The increased twisting moments produced by raising the center of gravity will be taken care of by the engagement of the wheels with the auxiliary bearing surfaces, 20 so that no excess pressure on the helical guide will result.

Figs. 9 and 10 show a modification of the invention in which special supporting ribs, such as 35 and 36, may be omitted, the wheels 25 of the cars being formed to engage the concave sides of trough 20 throughout the movement of the car through the helical guide. The guide rails X and Y and their coacting guide blocks 28^x and 28^y may be constructed 30 and disposed the same as in the preferred form already described. Also there are retained in this modification the straight horizontal ribs 33 and 34 onto which the wheels of the car pass from the outside traction 35 rails, the cars being supported on these horizontal ribs until their turning movement is initiated by the helical guides X and Y . As shown in Fig. 10, the car wheels are cut away 40 at their outer edges to form spherical surfaces 45 conforming to the curved sides of trough 20. Since the mean center of support of the car does not lie on the axis of the helical path of the car, it is evident that the tangency of these curved surfaces 45 to the 45 concave sides of the trough will relieve the helical guides of excess pressure. It would be possible to accomplish this same purpose by having the corner of the wheel rim touching the concave sides of the trough, but the 50 tendency in such case would be to cut grooves in the latter. Hence for practical purposes the corners are rounded as shown. Fig. 11 indicates a modification in which the relieving means is disposed outside the wheel rim, 55 and Fig. 12 shows a further modification in which the relieving surface is placed tangent to the wheel flange.

Figs. 13 to 15 illustrate still further modifications. In the construction shown therein 60 a separate helical rail for each wheel of the car is provided. Two spaced helical guide rails X and Y are used for coaction with guide blocks 28^x and 28^y on the car, as in the forms of invention above described. In 65 addition to these guides there are four rails

50, 51, 52 and 53 upon which respectively bear the four car wheels 50^x, 51^x, 52^x and 53^x. The rails 51 and 52 are horizontal and straight in the entrance (or exit) portion of the dump so as to receive the cars in horizontal position as they pass into the dump, or as they pass out of the dump. The rail 53 also has a straight horizontal end portion which is in alignment with rail 52. Rail 50 terminates at a point in the transverse 70 plane passing through the front axle of the car at the time when the car has engaged the helical guides X and Y , and is about to start rotating. After the car has turned through a small angle in its forward travel, wheel 51^x will engage rail 50 and roll thereon during the remainder of its helical movement through the dump. It will be observed from Fig. 13 that the end portion of rail 50 is out of vertical alignment with rail 51 so that rail 50 will not interfere with the movement of front wheel 50^x. The frame work for supporting the rails and guides is not shown but may be similar to the frame shown in connection with the preferred form of the 80 invention. 85

The invention is susceptible of various modifications other than those described, and it is therefore not intended to limit the scope of the invention except as defined by the 90 claims.

Having thus described the invention, what is claimed as new and desired to be secured by Letters Patent is:

1. Apparatus for dumping cars or the like comprising, in combination, a helical guide, a dump car adapted to be inverted and emptied as it is moved axially of said guide, two guide engaging members carried by said car, one in advance of the other, and both engaging said guide and supporting the car therefrom, the arrangement being such that the center of gravity of the loaded car lies in or close to the axis of the helical guide. 100

2. The combination with an open topped car of dumping apparatus therefor, the car and apparatus having inter-engaging portions whereby the car is caused to invert and right itself by revolution about a fixed axis as it moves longitudinally of the apparatus, the arrangement being such that the center of gravity of the car both when loaded and empty lies close to the axis about which the car revolves in its dumping movement. 110

3. The combination set forth in claim 2 in which the apparatus includes a helical guide and the car has guide engaging members positioned at its diagonally opposite corners. 120

4. In a dumping apparatus, in combination, a helical guide disposed with its axis substantially horizontal, and a car having guide engaging members, the car having a flat bottom and the guide engaging members 130

- being secured thereto beneath the car bottom at diagonally opposed corners.
5. The combination set forth in claim 4 in which the guide engaging members are provided with helical slots to receive the helical guide.
6. The combination with a plurality of cars connected together by swivel couplings positioned at or adjacent their centers of gravity, and each car having guide engaging means, of dumping apparatus, said apparatus including a helical guide adapted to be engaged successively by the car guide engaging means as the cars pass through said apparatus, whereby said cars may be successively dumped without being uncoupled.
- 10 7. Apparatus for dumping cars or the like, comprising, a helical guide, a dump car, two longitudinally and laterally spaced guide blocks carried by said car and provided with helically shaped surfaces for engaging said guide.
- 15 8. The combination set forth in claim 7 in which said guide blocks are located beneath the car respectively adjacent diagonally opposite corners thereof.
- 20 9. The combination set forth in claim 7 in which said guide and guide blocks are formed with engaging shoulders which enable the guide to support the car in all positions thereof.
- 25 10. The combination set forth in claim 7 in which said guide blocks have helical slots substantially T-shaped in cross section and said helical guide is formed to fit said slots.
- 30 11. In combination with a car dump comprising a helical guide which consists of two parallel members spaced from each other and having the same pitch and axis, of a car having two longitudinally and laterally spaced guide blocks formed with helical slots adapted respectively to engage said members.
- 35 12. The combination set forth in claim 11 in which one of said members terminates short of the other a distance substantially equal to the distance between the guide blocks whereby the blocks will be entered simultaneously by said members.
- 40 13. The combination set forth in claim 11 in which each of said members comprises a web and a flange.
- 45 14. The combination set forth in claim 11 in which each of said members comprises a web and a flange extending at an incline to the web.
- 50 15. A car dumping apparatus including in combination, a helical guide, means whereby a car may be supported on said guide in all positions of the car and caused thereby to invert and empty itself as it is moved axially through the guide, and auxiliary helical bearing surfaces for relieving excess pressure on the guide, said bearing surfaces adapted to be engaged by separate parts of the car structure.
16. The combination set forth in claim 15 in which said auxiliary bearing surfaces are so located that they will be engaged respectively by two wheels on the same side of the car.
- 70 17. The combination set forth in claim 15 in which said auxiliary bearing surfaces comprise helical surfaces located in the entrance portion of the apparatus adapted to be engaged by a pair of wheels on one side of the car and helical surfaces in the exit portion of the apparatus adapted to be engaged by a pair of wheels on the other side of said car.
- 75 18. In combination with a car dumping apparatus comprising a helical guide and auxiliary helical bearing members coaxial with the guide and of the same pitch, of a car having two longitudinally and laterally spaced helical blocks adapted to engage said guide, two wheels on the same side of said car being adapted to roll on said auxiliary bearing members.
- 80 19. A car dumping apparatus comprising a helical member having a trough-like form in cross section, a helical guide supported in the trough adapted to be engaged by a car, said trough having bearing surfaces adapted to be engaged by the wheels of the car.
- 85 20. The combination set forth in claim 19 in which said trough has concave sides curved substantially on the axis of said trough.
- 90 21. The combination set forth in claim 19 in which said bearing surfaces are presented by helical ribs extending along the sides of the trough.
- 95 100 22. The combination set forth in claim 19 in which said bearing surfaces are presented by a pair of helical ribs in the front portion of the trough for engagement by a pair of wheels on one side of a car and a pair of helical ribs in the rear portion of the trough for engagement by a pair of wheels on the other side of said car.
- 105 23. A car dump comprising a helical member having a trough-like form in cross section with the sides thereof curved substantially on the axis of the trough, a helical guide supported in the trough adapted to be engaged by a car, the rims of the car wheels being at all times tangent to the curved sides of the trough in the helical passage of the car through the dump.
- 110 24. The combination set forth in claim 23 in which the axis of the curved sides of the trough is eccentrically disposed with reference to the mean center of support of the car on said helical guide.
- 115 25. A car dump comprising a frame and a helical guide supported thereon in combination with a car having an open top body and having helical guide blocks on its under side adapted to engage said helical guide, whereby the points of support of the car on the helical guide will at all times in the passage of the car through the dump be located opposite
- 120 125 130

to the open side of the car, the pitch of the guide being sufficiently large so that no part thereof will obstruct the car opening in dumping.

26. The combination set forth in claim 25 in which said guide comprises a helical trough having a guide and support for the car located centrally therein, the sides of the trough being concavely curved so as to engage the wheel rims of a car at all times in the passage of the car through the dump.

27. Apparatus for dumping cars or the like comprising, in combination, a helical guide, a dump car adapted to be inverted and emptied as it is moved axially of said guide, coupling mechanism carried by said car, two guide engaging members carried by said car, one in advance of the other, and both engaging said guide and supporting the car therefrom, the arrangement being such that in dumping the axis of the couplings of the car remains substantially co-incident at all times with the axis of the helical guide.

28. Apparatus for dumping cars or the like comprising, in combination, a helical guide, a dump car adapted to be inverted and emptied as it is moved axially of said guide, two guide engaging members carried by said car, one in advance of the other, and both engaging said guide and supporting the car therefrom, the arrangement being such that the center of gravity of the car lies in or close to the axis of the helical guide, said guide engaging members being disposed out of parallel alignment with the axis of the helical guide.

29. Apparatus for dumping cars or the like comprising, in combination, a helical guide having a substantially horizontal axis, a dump car adapted to be inverted and emptied as it is moved axially of said guide, two guide engaging members carried by said car, one in advance of the other and both adapted to engage said guide upon entering the apparatus and support the car therefrom during the dumping movement, said guide engaging members being disposed out of parallel alignment with respect to the axis of the helical guide.

30. Apparatus for dumping cars or the like comprising, in combination, helical guide means having a substantially horizontal axis, a dump car, longitudinally spaced guide engaging members carried by said car, means provided in connection with said guide means whereby said guide engaging members are caused to engage said guide means simultaneously at spaced points along said guide means upon entering said apparatus and to disengage said guide means simultaneously at spaced points upon leaving said apparatus.

In testimony whereof I hereunto affix my signature.

JOHN D. PUGH.
